UNITED STATES PATENT OFFICE.

WILFRED E. ROYCE, OF LEAD, SOUTH DAKOTA.

PORTABLE ACETYLENE-LIGHTING APPARATUS.

1,170,935.

Specification of Letters Patent. Patented Feb. 8, 1916.

Application filed April 19, 1915. Serial No. 22,492.

To all whom it may concern:

Be it known that I, WILFRED E. ROYCE, a citizen of the United States, residing at Lead, in the county of Lawrence and State 5 of South Dakota, have invented certain new and useful Improvements in Portable Acetylene-Lighting Apparatus; and I do hereby declare the following to be a full, clear, and exact description of the invention, such as will enable others skilled in the art to which it appertains to make and use the same.

My invention relates to improvements in portable acetylene generators, and is intended to apply for use in connection with a portable acetylene light.

The invention belongs to that class of generators in which the calcium carbid is supplied to the apparatus in the crushed or granular state, and in which water is automatically supplied, in limited quantities, for the generation of gas when needed, and in which the supply of water is automatically cut off when the pressure of the gas in the apparatus exceeds the predetermined limit.

My invention will be understood by reference to the accompanying drawings, in which:

30 Figure 1 is a perspective view showing the complete apparatus; Fig. 2 shows a central vertical section through the apparatus of Fig. 1, on a larger scale, parts being shown in elevation and parts being broken away; Fig. 3 shows a section along the line 3—3 of Fig. 2, and looking down; and Fig. 4 is a detail showing in section, on a smaller scale, the carbid container detached from the apparatus, with the packing gasket supported thereon.

45 A represents a containing vessel of any suitable size or shape, preferably a cylindrical metallic bucket. Mounted in this container is the gas bell B, which is preferably in the form of a hollow cylinder with the top closed and the bottom open, and the top b of which is perforated to receive the gas pipe C opening therethrough.

50 D represents the carbid container which is separated by the diaphragm D' into an upper and a lower compartment. This diaphragm is pierced by a plurality of vertically-disposed tubes E, which tubes have imperforate shells projecting below the diaphragm D', and have the shells perforated,

as at e above said diaphragm. Supported on this diaphragm, and surrounding the perforated portions of the tubes E, is the crushed carbid F.

60 The carbid container D is provided with an outwardly-projecting flange d, which is attached to the top b of the gas bell B by means of screw bolts G and butterfly nuts G'. A packing ring N of rubber, or other suitable material, is inclosed between the flange d and the top b of the bell B to secure gas-tight joints about the bolt holes.

65 The receptacle A is preferably provided with a suitable handle comprising the ears H and the bail H', which bail is slotted, as at h, to permit the insertion of the upper end of the gas pipe C; and, when the apparatus is being transported, or is not in operation, the gas pipe C may be clamped at the desired position in said handle by means 70 of the swinging clamp I, held in place by the sliding sleeve I', see Figs. 1 and 2, or any other suitable clamping device may be used if desired.

75 The bail H' is held in an upright position by the sliding sleeve O slipping down over the ears H, see Figs. 1 and 2.

80 The upper end of the gas pipe C is provided with any suitable burner, but as illustrated in Fig. 1, I have shown a double elbow K, carrying the burner L and the reflector M, which elbow is so arranged that the burner and reflector may be turned to the desired position for throwing the light 85 in any desired direction.

90 The operation of the device is as follows:—A suitable quantity of water is poured into the receptacle A, and the carbid being placed in the container D, and the container being assembled in the bell B, as shown in Fig. 2, the two are dipped downwardly into the water and an air pocket will be formed beneath the diaphragm D', forcing the water to flow up through the bottom 95 of the tubes E and incidentally to rise to a relative height between the carbid container and the bell and between the bell and the receptacle A. As soon as the water rises high enough to flow through the perforations e, above the diaphragm D', acetylene 100 gas will be generated, which will create an upward pressure on the top b of the bell B, tending to drive down the water in the tubes E, and also to lift the bell B and with it 105 the carbid container, so that the upper level 110

of the water in the tubes will be pressed below the diaphragm, and thus the supply of water will be automatically cut off.

- The tubes E project down a considerable distance below the diaphragm D' so as to project beneath the surface of the water, and being imperforate the air is imprisoned in the space surrounding said tubes above the surface of the water, and below the bottom of the diaphragm D', which air will be compressed by the weight of the bell and will tend to keep the water up in the tubes and prevent the blowing down of the gas through the tubes into the water; thus providing a cushioning effect and tending to prevent as well as compensate for any sudden generation of the gas when the water flows through the smaller perforations above the diaphragm.
- 20 The gas may be turned on to the burner by means of any suitable cock, such as C', and the supply of gas will be automatically maintained as long as there is sufficient carbide in the container D. It will be obvious that the pressure of the carbide gas will vary with the weight of the gas bell and the parts carried thereby, and that if a heavier burner be put on top of the pipe C, or weights be applied to the top of the bell, greater gas pressure may be secured, and a more powerful burner may be used, thus the ordinary 16-candle power burner may be instantly changed for a 200-candle power burner.
- 35 As the water can reach the carbide only through the small tubes and perforations, there are no sudden variations in the generation of the gas, and these variations of pressure do not materially affect the appearance of the light.

In case it is desired to discontinue the light for any reason, the bell B is lifted up high enough in the receptacle A and the pipe C is clamped in the handle H' with the clamp I, when the entire apparatus will then be thrown out of commission; while it will be again thrown into operation instantly by lowering into the water.

It will be seen that the entire apparatus 50 may be picked up and carried bodily from place to place, and the burner and reflector may be turned to the desired position, throwing the light in any desired direction.

It will be seen that the apparatus is extremely simple and safe, and is absolutely automatic in its action. There are no valves to become clogged up with the residue from the gas, and any condensation is caught by the burner pipe and runs back into the light. 60 The only joints in its construction are those of the two elbows, to which are fastened the burner tip and the reflector, allowing them to be moved to any position. Moreover, the apparatus is highly economical for the reason that the amount of gas generated is con-

trolled by the weight of the burner used, which weight, of course, would vary with the size of the burner.

It will be obvious that various modifications might be made in the herein described apparatus and in the combination, construction and arrangement of parts which could be used without departing from the spirit of my invention.

I claim:—

1. An apparatus of the character described, comprising a receptacle adapted to contain water, a gas bell projecting down into said receptacle, a carbide container carried in the said bell and provided with a diaphragm extending transversely across the same and adapted to support the carbide, tubes projecting downwardly through said diaphragm and extending both above and below same, said tubes having perforations above said diaphragm and closed cylindrical side walls below said diaphragm, a gas pipe leading from the top of the bell, and a burner carried by said gas pipe, substantially as described.

2. An apparatus of the character described, comprising a receptacle adapted to contain water, a gas bell projecting down into said receptacle, a carbide container carried in the said bell and provided with a diaphragm extending transversely across the same and adapted to support the carbide, tubes projecting downwardly through said diaphragm and extending both above and below same, said tubes having perforations above said diaphragm and closed cylindrical side walls below said diaphragm, a gas pipe leading from the top of the bell, and a burner carried by said gas pipe, substantially as described.

3. An apparatus of the character described, comprising a receptacle adapted to contain water, a gas bell projecting down into said receptacle, a carbide container carried in the said bell and provided with a diaphragm extending transversely across the same and adapted to support the carbide, tubes projecting downwardly through said diaphragm and extending both above and below same, said tubes having perforations above said diaphragm and closed cylindrical side walls below said diaphragm, a gas pipe leading from the top of the bell, and a burner detachably connected to said gas pipe, substantially as described.

4. An apparatus of the character described, comprising a receptacle adapted to contain water, a gas bell projecting down into said receptacle, a carbide container carried in the said bell and provided with a diaphragm extending transversely across the same and adapted to support the carbide, tubes projecting downwardly through said diaphragm and extending both above and below same, said tubes having perforations

above said diaphragm and closed cylindrical side walls below said diaphragm, a gas pipe leading from the top of the bell, and a burner with a reflector carried thereby both 5 detachably connected to said gas pipe, substantially as described.

5. An apparatus of the character described, comprising a receptacle adapted to contain water, a gas bell projecting down 10 into said receptacle, a carbide container carried in the said bell and provided with a diaphragm extending transversely across the same and adapted to support the carbide, tubes projecting downwardly through said 15 diaphragm and extending both above and below same, said tubes having perforations above said diaphragm and closed cylindrical side walls below said diaphragm, a gas pipe leading from the top of the bell, and means 20 for clamping said gas pipe in the desired position for maintaining the apparatus out of operation when desired, substantially as described.

6. An apparatus of the character described, comprising a receptacle adapted to contain water, a gas bell projecting down 25 into said receptacle, a carbide container carried in the said bell and provided with a diaphragm extending transversely across the same and adapted to support the carbide, tubes projecting downwardly through said 30 diaphragm and extending both above and below same, said tubes having perforations

above said diaphragm and closed cylindrical side walls below said diaphragm, a gas pipe 35 leading from the top of the bell, a burner detachably connected to said gas pipe, a handle carried by said receptacle, and a clamp carried by said handle and adapted to clamp the said gas pipe in the desired position for 40 maintaining the apparatus out of operation when desired, substantially as described.

7. An apparatus of the character described, comprising a receptacle adapted to contain water, a gas bell projecting down 45 into said receptacle, a carbide container carried in the said bell and provided with a diaphragm extending transversely across the same and adapted to support the carbide, tubes projecting downwardly through said 50 diaphragm and extending both above and below same, said tubes having perforations above said diaphragm and closed cylindrical side walls below said diaphragm, a gas pipe 55 leading from the top of the bell, a burner and a reflector both detachably connected to said gas pipe, a handle carried by said receptacle, and a clamp carried by said handle and adapted to clamp the said gas pipe in the 60 desired position for maintaining the apparatus out of operation when desired, substantially as described.

In testimony whereof, I affix my signature.

WILFRED E. ROYCE.
